UNITED STATES PATENT OFFICE.

BENJAMIN B. GREER, OF CHICAGO, ILLINOIS.

MEANS FOR PREVENTING CREEPAGE OF RAILROAD RAILS.

Application filed July 19, 1920. Serial No. 397,255.

To all whom it may concern:

Be it known that I, BENJAMIN B. GREER, a citizen of the United States, residing at Chicago, in the county of Cook and State, 5 of Illinois, have invented certain new and useful Improvements in Means for Preventing Creepage of Railroad Rails, of which the following is a specification.

My invention relates to means for preventing creepage of railroad rails.

In the construction and maintenance of railroads it is common practice to provide anti-creeping devices to prevent longitudinal creeping of the rails on the ties, particularly on double track road where the traffic is mostly in one direction. These anti-creeping devices are often times complicated and inefficient and since they are embodied in structures separate and distinct from the rails or the usual tie plates the cost of track construction and maintenance is considerably increased. One of the objects of my invention is to provide holding means integral with the base of the rail which is adapted to engage the ties on which the rail rests in such a manner as to prevent effectively any substantial longitudinal movement of the rail with respect to the ties, when the spikes holding the rail are driven home. The holding means may take any one of several forms but preferably consists in ribs formed on the bottom of the rail base which may extend transversely of the rail and are adapted to work their way into the ties.

In most constructions, especially when ties of soft wood are used, it is common practice to provide metal plates between the rail base and the tie to provide a seat for the rail which will act in general to protect the ties and to prevent lateral turning of the rails about their longitudinal axes with the consequent cutting of the ties by the rail base. It is a further object of my invention to provide a tie plate having means interlocking with the holding means on the rail base whereby any substantial longitudinal creeping of the rail with respect to the plate is prevented when the rail and the plate are spiked to the tie. The tie plate may be formed with spike openings on both sides of and close to the edges of the rail base flanges whereby spikes driven there-through hold the rail and plate securely to the tie or the plate may be formed with an integral jaw adapted to

engage one side of the rail base, the opposite side of the rail base being held to the plate and tie by a spike. The interlocking holding means may take any one of several forms, for example, ribs may be provided on the bottom of the rail base adapted to interlock with suitable grooves formed in the upper side of the tie plate, or when a tie plate of the type last mentioned is used the ribs may be formed on the top of the rail base flange and the grooves in the underside of the jaw provided on the tie plate. Preferably the ribs and grooves are V-shaped and extend transversely of the rail base, the grooves being formed a little wider than the ribs to permit limited longitudinal movement of the rail to take care of contraction and expansion which occur under changes of temperature.

The invention consists in certain novel arrangements and constructions, to be hereinafter described and claimed, whereby the above stated objects and such other objects as will hereinafter appear, are obtained.

The invention is illustrated in certain preferred embodiments in the accompanying drawings wherein:

Fig. 1 is a side elevation of a section of rail, embodying the principles of my invention, as applied directly to the ties.

Fig. 2 is a perspective view of a section of the rail with a tie plate, constructed according to my invention disposed between the rail base and the tie, the tie plate having a jaw adapted to engage one of the rail base flanges.

Fig. 3 is an enlarged elevational view of the parts shown in Fig. 2 looking from the left hand side of the figure.

Fig. 4 is a perspective view of a section of the rail illustrated in the preceding figures.

Fig. 5 is a perspective view of a tie plate adapted to cooperate with the rail base to prevent creeping of the rail, but without the overhanging jaw, and

Fig. 6 is a perspective view of a rail base and a tie plate illustrating a modification.

Like characters of reference designate like parts in the several views.

Referring first to Figs. 1 to 4, inclusive, the rail 7 is formed so as to provide integral holding means on the base thereof adapted to engage the ties on which the rail rests. The holding means preferably is

in the form of ribs 8 which may extend transversely of the rail base. These ribs are preferably V-shaped and are adapted to work their way into the upper side of the 5 cross-ties 9 when the rail is placed directly on the ties, as shown in Fig. 1, the rail being secured to the ties by any preferred means, for example, the spikes 10. The ribs are integrally formed with the rail base at 10 the time the rail is rolled at practically no extra cost. With a rail constructed as above described every tie does its share in holding the rail against longitudinal creeping and in effect becomes a rail anchor. The 15 weight of the rolling stock in passing over the rail forces the ribs to their maximum depth into the tie thereby increasing the effectiveness of the engagement between the ribs and the ties. The fibres of the ties 20 adjacent the grooves formed in the upper sides thereof by the ribs on the rail base yield sufficiently to permit limited longitudinal movement of the rail resulting from contraction or expansion due to changes in 25 temperature.

In Figures 2 and 3 I have shown a rail, embodying the principles of my invention, with a special form of tie plate 11 interposed between the base of the rail and the tie. 30 The tie plate is preferably provided along one of its longitudinal edges with an integral jaw 12. This jaw is preferably formed so that it will overhang one of the base flanges of the rail and so that the angularity 35 of the surface 13 of the underside of the jaw is less than the angularity of the top surface of the base flange 7^a of the rail and consequently the jaw will have to be forced upwardly slightly and will take a firm pinching grip on the base flange when the same is 40 forced into the jaw, as shown in Fig. 2. The upper side of the tie plate is provided with a series of grooves 14 which are uniformly spaced according to the spacing of 45 the ribs on the bottom of the rail base and are adapted to receive said ribs. As more clearly shown in Fig. 3 the grooves 14 are slightly larger than the ribs 8 thus making provision for such limited longitudinal 50 movement of the rail with respect to the tie plate as may take place due to contraction and expansion. The tie plate adjacent the jaw 12 is provided with one or more spike 55 openings 15, the opposite edge of the plate being also provided with one or more spike openings 16. One edge of the base flange of the rail is forced in under the jaw 12, the ribs 8 projecting into the grooves 14, the opposite edge of the rail base and side of the 60 tie plate being secured to the tie by the spikes 10 which project through the openings 16. By this arrangement the rail is positively held against any substantial longitudinal movement by the interlocking 65 surfaces of the rail base and the tie plate.

In Fig. 5 is shown a tie plate similar to the plate shown in Figs. 2 and 3, the jaw 12, however, being omitted and the rail base flange on the right hand side being held down by spikes in the same manner as the 70 flange on the other side is held down in the Figs. 2 and 3.

In the modification shown in Fig. 6 the ribs 8^a are formed on the upper side of the flanges of the rail base and the grooves in 75 the tie plate are formed in the under side of the jaw 12^a, the tie plate in other respects being similar to the one shown in Figs. 2 and 3. It will be obvious that various other modifications might be made without departing from the principles of my invention. I do not intend to limit the invention, therefore, to the constructions and arrangements shown and described herein except only in so far as certain of the appended claims are 80 specifically so limited.

I claim:

1. The combination of a railroad rail and a tie plate, said plate being provided on one side with a jaw adapted to fit one edge 90 of the rail base and bear against the upper surface thereof and on the other side with a spike opening, the base of the rail having transverse ribs formed on the bottom and extending to an edge thereof and the plate having grooves in its upper surface adapted to receive said ribs and permit the plate being applied by driving the same transversely of the rail, the grooves being of greater width than the ribs thereby permitting limited longitudinal movement of the rail relative to the plate.

2. The combination of a railroad rail and a tie plate, said plate being provided on one side with a jaw adapted to overhang one of 105 the base flanges of the rail and on the other side with a spike opening, the angularity of the under surface of the jaw being less than that of the top surface of the base flange of the rail, the base of the rail and the plates 110 having interlocking surfaces adapted to prevent any substantial relative movement.

3. The combination of a railroad rail and a tie plate, said plate being provided on one side with a jaw adapted to overhang one 115 of the base flanges of the rail and on the other side with a spike opening, the angularity of the under surface of the jaw being less than that of the top surface of the base flange of the rail, the base of the rail having 120 integral ribs formed thereon and the plate having grooves adapted to receive the ribs.

4. The combination of a railroad rail and a tie plate, said plate being provided on one side with a jaw adapted to overhang 125 one of the base flanges of the rail and on the other side with a spike opening, the angularity of the under surface of the jaw being less than that of the top surface of the base flange of the rail, the base of the rail having 130

transverse ribs formed on the bottom thereof and the plate having grooves in its upper surface adapted to receive said ribs.

5. The combination of a railroad rail and a tie plate, said plate being provided on one side with a jaw adapted to overhang one of the base flanges of the rail and on the other side with a spike opening, the angularity of the under surface of the jaw being less than that of the top surface of the

base flange of the rail, the base of the rail having transverse ribs formed on the bottom thereof and the plate having grooves in its upper surface adapted to receive said ribs, the grooves being of greater width than 15 the ribs thereby permitting limited longitudinal movement of the rail relative to the plate.

BENJAMIN B. GREER.
